UNITED STATES PATENT OFFICE

2,488,254

DISPENSER

Duncan G. Allen, Houston, Tex.

Application December 30, 1947, Serial No. 794,683

1 Claim. (Cl. 222—128)

1

This invention relates to new and useful improvements and structural refinements in dispensers, and the principal object of the invention is to provide a device of the character herein described, such as may be conveniently and effectively employed as a dispensing container for sugar, salt, and other substances in granulated or powder form.

A further object of the invention is to provide a dispenser from which the contents may be quickly and easily withdrawn and which may be refilled with equal expediency.

Another object of the invention is to provide a dispenser which is simple in construction, pleasing in appearance, and which will readily lend itself to economical manufacture.

An additional object of the invention is to provide a dispenser which is otherwise well adapted for the purpose for which it is used.

With the above more important objects in view and such other objects as may become apparent as this specification proceeds, the invention consists essentially of the construction and arrangement of parts as shown in the accompanying drawings in which:

Figure 1 is a perspective view of the invention.

Figure 2 is a vertical cross sectional view thereof, and

Figure 3 is a cross sectional view, taken substantially in the plane of line 3—3 in Figure 2.

Like characters of reference are employed to designate like parts in the specification and throughout the several views.

Referring now to the accompanying drawings in detail, the invention consists of a dispenser designated generally by the reference character 10, the same embodying in its construction a substantially cylindrical receptacle 11 disposed in a vertical position and provided at the upper end thereof with a removable cover 12.

The marginal edge portion of this cover is either corrugated or screw threaded as at 13 to engage a correspondingly configurated portion 14 formed at the upper end of the receptacle 11, whereby the cover is removably retained in position on the receptacle, as will be clearly understood.

The lower end portion of the receptacle 11 is restricted to provide what may be referred to as a common discharge and refill opening 15, this opening merging at its inner end into a frusto-conical discharge throat portion 16 of the receptacle, while the outer end of the opening 15 merges into a frusto-conical refilling throat 17.

A vertically disposed, tubular sleeve 18 is se- 55

2

cured at the upper end thereof to the inner surface of the aforementioned cover 12, the lower end of the sleeve being open and the cover 12 being formed with a central aperture 19 to slidably accommodate a plunger rod 20. This rod is disposed axially in the receptacle 11, the upper end portion of the rod projecting above the cover 12 and being provided with a convenient hand knob 21.

10 A closure member 22 is secured or provided integrally with the lower end of the rod 20, and a tubular spring retainer 23 is mounted on the midportion of the rod 20 as will be presently described.

15 The retainer 23 is provided at its lower end with a closed end wall 24 secured to the rod 20, while the upper end of the retainer is open. Moreover, the retainer 23 is slidably telescoped into the aforementioned sleeve 18, and a spring 20 25 is secured at one end thereof to the end wall 24 of the retainer 23 while the remaining end of the spring is similarly secured to the cover 12.

When the invention is placed in use, the contents of the receptacle 11 may be dispensed by 25 simply pressing the knob 21 downwardly in the direction of the arrow 26, so as to project the closure member 22 through the opening 15 to a position shown by the phantom lines 27. In this manner, the contents of the receptacle 11 30 will be caused to gravitate along the downwardly convergent surfaces of the frusto-conical throat 16 and then through the opening 15, as will be clearly apparent.

It is to be noted that as the member 22 is 35 projected to its discharge position shown at 27, the spring 25 will become stretched, and when subsequently, downward pressure upon the knob 21 is relaxed, the spring 25 will automatically return the member 22 to its normal position 40 within the opening 15. While in this normal position, the opening 15 is closed by the member 22, and discharge of the contents of the receptacle 11 is prevented.

When it is desired to refill the receptacle 11, 45 this may be accomplished by simply inverting the entire dispenser and pulling the knob in the direction of the arrow 28. Under such circumstances, the member 22 will be retracted into the receptacle to a position indicated at 29, whereupon material may be poured, so to speak, into the receptacle through the opening 15. This pouring action will, of course, be facilitated by the provision of the frusto-conical throat 17, which will function in the manner of a funnel.

It may be added that the primary purpose of

the sleeve 18 and retainer 23 is to provide a cover, so to speak, for the spring 25, so that the spring does not come into direct contact with the contents of the receptacle.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

A dispenser comprising in combination, an upright receptacle having a cover at the upper end thereof, the lower end of said receptacle being provided with a common discharge and refill opening, a tubular sleeve provided in said receptacle and secured to said cover, an externally manipulable plunger rod slidable in said receptacle and extending through said sleeve, a tubular spring retainer secured to said rod in telescoped relation to said sleeve, a spring attached

at one end to said cover and at its remaining end to said retainer, and a closure member secured to said rod, said member normally closing said opening and being selectively projectable and retractable therethrough.
